(57) **CLAIM**

The ornamental design for a remote control leash, as shown and described.

DESCRIPTION

FIG. 1 is a front elevational view of a remote control leash showing my new design;

FIG. 2 is a rear elevational view thereof;

FIG. 3 is a side view, taken from the left side of FIG. 1, the right side view being a mirror image thereof;

FIG. 4 is a top plan view thereof;

FIG. 5 is a bottom plan view thereof; and,

FIG. 6 is a perspective view thereof.

The broken line showing a remote control in FIG. 6 is for illustrative purposes only and forms no part of the claimed design.

The remote control leash is shown in FIGS. 1-3 broken away for ease of illustration.
